(57) **CLAIM**

We claim the ornamental design for an ozone generator, as shown and described.

DESCRIPTION

FIG. 1 is a front perspective view of an ozone generator of the present invention;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof; and,

FIG. 8 is a cross-sectional view taken along the line **8-8** of FIG. 2 thereof.

The broken lines shown represent unclaimed subject matter and form no part of the claimed design.
